UNITED STATES PATENT OFFICE.

JOHN R. VOSBURGH, OF JOHNSTOWN, NEW YORK.

HAND-GRIP.

1,356,572.

Specification of Letters Patent. Patented Oct. 26, 1920.

Application filed April 21, 1919. Serial No. 291,465.

To all whom it may concern:

Be it known that I, JOHN R. VOSBURGH, a citizen of the United States, residing at Johnstown, in the county of Fulton and 5 State of New York, have invented certain new and useful Improvements in Hand-Grips; and I do hereby declare the following to be a full, clear, and exact description of the invention, such as will enable others 10 skilled in the art to which it appertains to make and use the same.

This invention relates to improvements in hand grips and to a method of making the same. The improved grips are particularly designed for use with bicycle and motorcycle handle bars, but the same construction may be employed for other uses, 15 such as golf clubs, polo clubs, hand levers and the like.

20 The principal object of the invention is to provide a yielding hand grip, which by reason of its resiliency will effectively absorb shocks and will not transfer vibrations to the hand of the user. By the use of the 25 grip, in connection with bicycle and motorcycle handle bars, travel jars will be absorbed and the rider will not be fatigued as he is when using a non-yielding grip.

Another object of the invention is to produce a yielding hand grip of simple and inexpensive construction.

With the foregoing objects outlined and with other objects in view, which will appear as the description proceeds, the invention 35 consists in the novel method and features hereinafter described in detail in connection with the accompanying drawing, and more particularly pointed out in the appended claims.

40 Referring to the drawings;

Figure 1 is a perspective view of a portion of a handle bar showing one form of my improved grip mounted on the same.

Fig. 2 is a longitudinal sectional view of 45 one form of the improved grip.

Fig. 3 is a transverse sectional view of the same.

Fig. 4 is a side view partly in section of a modified form of grip.

50 In the drawing, 1 designates the foundation of the grip and it is formed of animal skin with the fur left on, preferably un-sheared sheep skin. The foundation is preferably made of two similar pieces 2 having their edges secured together by suitable means such as threads 3. The flesh

side of the pieces 2 is designated 4 and the fur 5. The foundation is of cylindrical shape and preferably has one closed end 6. Stiffness is imparted to the foundation by 60 "laying off" over a steam heated iron and by moistening the leather of the foundation, which hardens under the heat. The "laying off" also gives shape to the foundation. 65

The foundation is incased in a cover 7 of any suitably flexible material, such as soft leather, and in making up the cover, a cylinder 8 is first formed by stitching the side edges of a blank and then sewing 70 a disk to one end of the cylinder to form a head 9. The stitches are applied while the casing is reversed and after the casing is made, it is turned inside out in order to place the seams 10 on the interior of the 75 cover, as shown in Figs. 2 and 3.

After the casing and foundation are formed, the casing is drawn over the foundation until the edges at the open ends of the parts meet. At this time, these edges 80 are sewed together, as shown at 11 and then the foundation is forced into the casing until a portion of the casing is turned inwardly, as shown at 12, in order to provide a neat and smooth appearance at the open 85 end of the grip.

To prevent the part 12 from crowding when it is turned inwardly, I preferably taper the open end of the casing, as shown at 13. 90

Subsequent to the sewing of the stitches 11, the foundation is laid off and shaped in the manner heretofore mentioned.

By this construction, a grip is provided in which the soft covering will form a 95 smooth grasping surface for the hand and the fur or wool will provide a yielding shock absorber.

The construction shown in Fig. 4 is similar to that already described with the exception that an inner casing 15 is provided between the cover 7^a and the foundation 1^a. This inner casing is formed of inexpensive material, such as cowhide split leather, which gives smoothness to the exterior 105 cover, obviates unevenness in the wool or fur-filling, and permits re-covering. This construction provides a better finish at the open end, by reason of the inner casing projecting slightly beyond the foundation as 110 shown at 16, and when the outer covering is drawn over it, the edge of the open end

- will be smooth and straight. The inner casing 15 has its inner surface coated with glue 17 which is permitted to dry before the inner casing is placed over the foundation, and in laying off the foundation, the hot steam causes the glue to soften and adhere to the wool or fur of the foundation and in consequence, the inner casing will be very firmly united with the foundation.
- 10 It is obvious that the grip may be manufactured with both ends open, in which case the foundation will be made slightly shorter than the cover and both ends of the cover will be turned inwardly.
- 15 Particular attention is directed to the fact, that by my construction, a grip is provided which has no seam with threads exposed to wear and consequently the grip will last for a great length of time.
- 20 This invention is not limited to the exact details shown and described but it includes in its scope such constructions and procedures as are included in the following claims.
- 25 What I claim and desire to secure by Letters Patent is:—
1. A hand grip including a tubular foundation, yielding soft material integral with the foundation and arranged on the exterior of the same, and a flexible covering engaging said soft material and inclosing the same.
  2. A hand grip comprising a foundation formed of animal hide with the fur unremoved, and a flexible covering inclosing said foundation, the fur of said foundation being located between the leather of the hide and said covering.
  3. A hand grip comprising a cylindrical foundation formed of unsheared animal skin, the fur of said foundation forming the exterior surface of the foundation, and a flexible covering inclosing said foundation and engaging said fur.
  4. A hand grip comprising a hollow foundation formed of unsheared animal skin, the flesh side of the skin forming the interior of the foundation and the fur forming the exterior, and a flexible covering inclosing said foundation and having one of its ends turned inwardly and secured to the foundation.

5. A hand grip comprising a hollow foundation formed of unsheared animal skin, the flesh side of the skin forming the interior of the foundation and the fur forming the exterior, a flexible inner casing inclosing the foundation and secured to the foundation, and an outer covering inclosing the inner casing and foundation.

6. A hand grip comprising a hollow foundation formed of unsheared animal skin, the flesh side of the skin forming the interior of the foundation and the fur forming the exterior, a flexible inner casing surrounding the foundation and secured to the fur by an adhesive substance, and an outer covering inclosing the inner casing.

7. A method of making hand grips, which consists in forming a hollow foundation of unsheared animal skin, the flesh side of the skin being placed interiorly and the fur being placed exteriorly, placing a flexible cover over said skin, securing the cover to the skin, moistening the flesh side of said skin, and heating and shaping the foundation by applying a heated former to the interior of the same.

8. A method of making hand grips, which consists in forming a hollow foundation of unsheared animal skin, the flesh side of the skin being placed interiorly and the fur being placed exteriorly, inserting said foundation in a tubular flexible covering, securing the cover to the skin, moistening the flesh side of said skin, and shaping and stiffening the foundation by applying a heated former to the interior of the same.

9. A method of making hand grips, which consists in forming a hollow foundation of unsheared animal skin, the flesh side of the skin being placed interiorly and the fur being placed exteriorly, inserting said foundation in a tubular flexible covering which has its inner surface coated with adhesive material, placing an outer covering over said flexible covering, moistening the flesh side of said skin, and simultaneously shaping and stiffening the foundation, and softening the adhesive substance, by applying a heated former to the interior of the foundation.

In testimony whereof I affix my signature.

JOHN R. VOSBURGH.
